UNITED STATES PATENT OFFICE.

WILLIAM BECKSTEIN, OF WASHINGTON, DISTRICT OF COLUMBIA.

DESIGN FOR A BREAD-PAN.

SPECIFICATION forming part of Design No. 19,696, dated March 11, 1890.

Application filed February 13, 1890. Serial No. 340,370. Term of patent 7 years.

To all whom it may concern:

Be it known that I, WILLIAM BECKSTEIN, a citizen of the United States, and a resident of the city of Washington, in the District of Columbia, have invented a novel Design for Bread-Pans, of which the following is a specification.

My invention is a novel design for bread-pans.

In the drawings, Figure 1 is a plan view of a pan embodying my design; and Fig. 2 is a side elevation, and Fig. 3 is a perspective view, thereof.

The leading feature of the design is the peculiar shape of the body A of the pan, which, as shown, is open at the top, as usual, and is

rounded transversely, and tapers gradually in curved lines in opposite directions from its longitudinal center to the ends a a, thus presenting to the eye a shell-like structure with 20 pointed ends, curved sides, and a rounded bottom.

What I claim is—

A design for bread-pans, substantially as herein shown and described. 25

In testimony whereof I have signed my name to this specification in the presence of two subscribing witnesses.

WILLIAM BECKSTEIN.
